UNITED STATES PATENT OFFICE.

ELIJAH S. BUCKLEY, OF NEW BERLIN, NEW YORK.

BELT-JOINT.

SPECIFICATION forming part of Letters Patent No. 752,512, dated February 16, 1904.

Application filed May 6, 1903. Serial No. 155,936. (No model.)

To all whom it may concern:

Be it known that I, ELIJAH S. BUCKLEY, a citizen of the United States, residing at New Berlin, in the county of Chenango and State of New York, have invented new and useful Improvements in Belt-Joints, of which the following is a specification.

This invention relates to belt-joints, the object in view being to provide a simple, cheap, effective, and reliable joint or connection by means of which the ends or extremities of a driving-belt may be firmly secured together in the same plane.

The parts of the joint are so constructed and related to each other that they may be quickly applied to the extremities of the belt and firmly secured thereto in a short space of time.

With the above and other objects in view the invention consists in the novel construction, combination, and arrangement of parts, which will be hereinafter fully described, illustrated, and claimed.

In the accompanying drawings, Figure 1 is a perspective view of the improved belt-joint, showing the belt ends associated therewith. Fig. 2 is an enlarged central longitudinal section through the same. Fig. 3 is a plan view of one of the joint members, and Fig. 4 is a similar view of the other joint member.

Like reference-numerals designate corresponding parts in all figures of the drawings. The belt-joint contemplated in this invention is separable from the belt proper and is composed, essentially, of two members 1 and 2, each of which is substantially rectangular and nearly square in plan and are the same width as the belt-joint. The member 1 is provided with a central closed slot 3, while the material of said member along one side of the slot is chamfered, as shown at 4. The slot 3 is approximately equal to or greater than one-half of the length of the member 1. The member 2 is of the same size as the member 1; but instead of a single central closed slot the member 2 is provided with oppositely-arranged open slots 5, or, in other words, slots which open out at the sides of the member 2. The

side walls of the slots 5 are chamfered, as shown at 6, to correspond with the chamfered edge 4 of the slot 3. By providing the open slots 6 an intermediate neck 7 is left between the slots. This neck is adapted to be received in and passed through the closed slot 3 of the member 1 in the manner illustrated in Figs. 55 1 and 2. The joint members are preferably composed of leather or other similar flexible and tough material, which will enable the corner portions of the member 2 to be folded in such position as to adapt them to be passed 60 through the slots 3 of the member 1. In this way the two members are associated and brought into the relation illustrated in Figs. 1 and 2, thereby forming two sets of parallel leaves 8 and 9, between which the extremities 65 10 of the belt are placed, as shown in Figs. 1 and 2, and secured firmly by means of rivets 11. Said rivets may be of any usual or preferred form, those shown being of the split type, which are clenched, as shown at 12, 70 against the reverse side of the joint members from which the rivets are entered.

From the foregoing description and the accompanying illustration it will be seen that the extremities of the belt lie in alinement. 75 It will also be seen that by reason of the fact that the joint members 1 and 2 intersect each other any tensile strain brought to bear on the belt will tend to force the central portions of the members 1 and 2 more closely together 80 and in contact with the extremities of the belt. One or more rows of rivets may be passed through each set of parallel leaves 8 and 9, according to the strain to which the driving-belt may be subjected in use. 85

Having thus described the invention, what is claimed as new is—

The combination with the meeting ends of a belt, of a belt-joint composed of two strips of flexible material having equal dimensions, 90 the one strip being formed with transverse slots extending partially thereover and opening out through the opposite side edges thereof, said slots being in alinement to form inwardly-foldable end members, and the other 95 strip having a slot located in the center there-

of and extending transversely of the same, the latter slot being equal in length to the distance between the inner terminal of the slots in the first-named strip and adapted to have the fold-
5 able members of said first-named strip inserted therethrough, the oppositely-projecting portions of the joint embracing the opposite sides of the belt ends, and means for securing

the said oppositely-projecting portions of the joint to the belt ends.

In testimony whereof I affix my signature in presence of two witnesses.

ELIJAH S. BUCKLEY.
